CLAIM

The ornamental design for a leg garment, as shown and described.

DESCRIPTION

FIG. 1 is a left perspective view of a leg garment in accordance with the claimed design;
FIG. 2 is a front perspective view of the design of FIG. 1;
FIG. 3 is a right perspective view of the design of FIG. 1;
FIG. 4 is a rear perspective view of the design of FIG. 1;
FIG. 5 is a left perspective view of the design of FIG. 1;
FIG. 6 is a bottom perspective view of the design of FIG. 1;
FIG. 7 is a top perspective view of the design of FIG. 1;
FIG. 8 is a front perspective view of the design of FIG. 1 with a foot portion unwrapped on a flat surface;
FIG. 9 is a rear perspective view of the design of FIG. 1 with a foot portion unwrapped on a flat surface;
FIG. 10 is an elevation perspective view of the design of FIG. 1 as configured in FIG. 9;
FIG. 11 is a perspective view of the design of FIG. 1 as configured in FIG. 9; and,
FIG. 12 is a side perspective view of the design of FIG. 1 with a foot portion unwrapped.
The dash-dash broken lines in the figures represent environment in which the claimed design may be embodied, and which form no part of the claimed design.

1 Claim, 12 Drawing Sheets
